UNITED STATES PATENT OFFICE

94,201

DESIGN FOR A FLATIRON

Harold C. Genter, Minneapolis, Minn., and James S. Ness, Chicago, Ill., assignors to Waters-Genter Company, Minneapolis, Minn., a corporation of Minnesota

Application October 8, 1934, Serial No. 53,525

Term of patent 7 years

To all whom it may concern:

Be it known that we, Harold C. Genter and James S. Ness, both citizens of the United States, residing at Minneapolis, Hennepin County, Minnesota, and Chicago, Cook County, Illinois, respectively, have invented a new, original, and ornamental Design for a Flatiron, of which the following is a specification, reference being had to the accompanying drawing, forming part thereof, and in which

Figure 1 is a side view of a flatiron, showing our new design;

Figure 2 is a plan view of Figure 1; and

Figure 3 is an end view of Figure 1.

We claim:

The ornamental design for a flatiron, as shown.

HAROLD C. GENTER.
JAMES S. NESS.
